UNITED STATES PATENT OFFICE.

WILLARD R. WOOD, SR., OF HEDGESVILLE, NEW YORK.

AUTOMATIC CAR-BRAKE.

SPECIFICATION forming part of Letters Patent No. 395,104, dated December 25, 1888.

Application filed January 21, 1888. Serial No. 261,475. (No model.)

To all whom it may concern:

Be it known that I, WILLARD R. WOOD, Sr., of Hedgesville, in the county of Steuben and State of New York, have invented a new and 5 Improved Automatic Car-Brake, of which the following is a full, clear, and exact description.

The object of the invention is to provide a new and improved car-brake which is simple 10 and durable in construction and very effective in operation.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

20 Figure 1 is an inverted plan view of a car provided with the improvement. Fig. 2 is a longitudinal sectional side elevation of the same on the line *x x* of Fig. 1. Fig. 3 is a like view of the same on the line *y y* of Fig. 1. 25 Fig. 4 is a transverse sectional elevation of the improvement on the line *z z* of Fig. 1, and Fig. 5 is a sectional side elevation of parts of the improvement on the line *w w* of Fig. 4.

The car A, of any approved construction, 30 is provided with the usual axles, B, B', B², and B³, carrying the wheels C in the usual manner. On the axle B is secured a pinion, D, adapted to be engaged by a segmental gear-wheel, E, fastened on a shaft, F, mounted to 35 rotate in yielding bearings G, held to slide vertically in the slotted standards H, through the lower parts of which passes the axle B, the upper parts being provided with a cross-plate, H', held in place by a rod, H², secured to the 40 car A. The bearings G are held in their uppermost position by springs I, held in the standards H and exerting an upward pressure against the said bearings G. The bearings G are united at their upper ends by a 45 cross-pin, J, on which operates a double wedge, K, provided with the inclines K' and K², extending in opposite directions and adapted to operate on the top of said pin J. The double wedge K rests with its upper edge under the 50 top plate, H', of the standard H, and the ends of the said double wedge K are connected

with the brake-rods L and L', extending in opposite directions to the front and rear ends of the car, and are connected in the usual manner with the brake-staffs of the car, so 55 that when the latter are operated said double wedge K is moved forward or backward.

On the shaft F, carrying the segmental gear-wheel E, is secured a sprocket-wheel, N, over which passes a sprocket-chain, O, also passing 60 over a sprocket-wheel, P, secured on a shaft, Q, mounted to rotate in suitable bearings formed on the under side of the car A. On the shaft Q is fastened a drum, R, on which are adapted to be wound the chains S and S', 65 extending in opposite directions and connected with the springs T and T', respectively, which are connected with the chains U and U', respectively, extending to the brake-beams V and V', operating in the usual manner on the car-wheels C of the axles B and B². 70

The brake-beams V are connected with a second set of brake-beams, V', by means of the links V², and the said second set of brake-beams, V', operate on the wheels C of the axles 75 B' and B³ whenever the beams V are set in motion and act on the wheels of the axles B and B², so that the brakes are all applied simultaneously.

The end teeth, E' and E², of the segmental 80 gear-wheel E are fulcrumed on the latter and connected with each other at their inner ends by a spring, E³. (Plainly shown in Fig. 5.) The said pivoted teeth are for the purpose of preventing a jar when the pinion-wheel comes 85 to the last tooth on the segmental wheel, and to make a smooth surface for it to pass over in reaching the place on the segmental wheel where it holds the brake on the wheels.

The operation is as follows: When the car 90 is running, the gear-wheel D is disengaged from the segmental gear-wheel E, as the latter is held in an uppermost position by the springs I pressing against the bearings G. The pin J of the latter rests between the inclines K' and K² of the double wedge K, and when the operator now desires to apply the brakes he pulls on the brake-rod L or L', so that the respective incline K' or K² acts on the top of the pin J, whereby the latter with 95 the bearings G is pressed downward, so that the segmental gear-wheel E is thrown in mesh 100

with the gear-wheel D. The rotary motion of the latter on the forward movement of the car imparts a rotary motion to the segmental gear-wheel E and its shaft F, and the latter, 5 by the sprocket-wheel N, the sprocket-chain O, and the sprocket-wheel P, imparts a rotary motion to the shaft Q, so that the chains S and S' are wound upon the drum R and the springs T and T' are compressed. At 10 the same time that the latter takes place a pressure is exerted against the brake-beams V by the said compressed springs T and T' and the chains U and U', so that all the brake-beams V and V' are acted on simultaneously 15 and thrown in contact with the car-wheels C, thus breaking them. When the gear-wheel D has imparted one-quarter of a revolution to the segmental gear-wheel E, it comes in contact with the pivoted outer tooth, E' or E², respectively, 20 thus preventing a further rotary motion of the said wheel E, and thereby holding the brakes applied. It will be seen that the teeth of the gear-wheel D press the pivoted teeth E' or E² against the next following 25 fixed tooth of the segmental gear-wheel E, so that the return movement of the segmental gear-wheel E is prevented.

When the operator desires to release the brakes, he pulls the brake-rod L or L' in an 30 opposite direction, so that the respective incline K' or K² disengages the pin J and the springs I force the bearings G upward, and thereby throw the segmental gear-wheel E out of contact with the gear-wheel D. The 35 compressed springs T now exert their pressure and unwind the chains S and S' from the drum R by rotating the latter, and at the same time release the brakes. The rotary motion of the drum R, caused by the pressure 40 of the springs T T', as above mentioned, rotates the shaft F in an opposite direction, so that the segmental gear-wheel E is given a quarter of a turn until it resumes its original position, as shown in Fig. 5. Thus it will be 45 seen that it is only necessary in order to apply the brakes or to release them to impart a sliding motion to the brake-rod L or L', so that the double wedge K acts with its inclines K' and K² on the pin J of the bearing G, 50 whereby the segmental gear-wheel E is moved in or out of contact with the gear-wheel D, secured on one of the axles of the car.

Instead of using the gear-wheels D and E, as shown, I may use friction-wheels for accomplishing the same result. Instead of connecting the rods L and L' with the brake-staffs of each individual car, I may connect the rods L and L' with the corresponding rods L' or L of the next following car and

the brake-rod of the car next to the locomotive with the cab of the latter, so that the engineer can control and operate all the brakes on the train whenever he desires. 60

Having thus fully described my invention, I claim as new and desire to secure by Letters 65 Patent—

1. In a car-brake, the combination, with a gear-wheel secured to one of the axles of a car-truck, of a segmental gear-wheel adapted to engage the said gear-wheel on the axle, 70 yielding bearings carrying the said segmental gear-wheel, and a double wedge engaging the said yielding bearings and operated from the brake-staffs so as to move the said segmental gear-wheel in or out of mesh with the said 75 wheel on the axle, substantially as shown and described.

2. In a car-brake, the combination with a gear-wheel secured to one of the axles of the car-truck, of a segmental gear-wheel adapted 80 to engage the said gear-wheel on the axle, a sprocket-wheel connected and rotating with the said segmental gear-wheel, a second sprocket-wheel connected by a chain with the said first-named sprocket-wheel, a shaft carrying the said second sprocket-wheel and provided with a drum, chains adapted to be wound on the said drum, and springs connected with the said chains and also connected with the brake mechanism, substantially as 85 shown and described.

3. In a car-brake, the combination, with a double wedge operated by the brake-staff, of a bearing having a pin on which said double wedge acts, springs pressing against the said 95 bearing for holding it in its uppermost position, a shaft mounted to rotate in the said bearings and connected with the brake mechanism, and a segmental gear-wheel held on the said shaft and adapted to be thrown in 100 mesh with the gear-wheel on one of the axles of the car-truck, substantially as shown and described.

4. In a car-brake, the combination, with a segmental gear-wheel provided at its ends 105 with pivoted teeth and a spring connected with the said pivoted teeth, of yielding bearings carrying the said segmental gear-wheel and provided with a pin, a double wedge acting on the pin of the said bearings, and a 110 gear-wheel secured to one of the axles of the car-truck and adapted to be engaged by the said segmental gear-wheel, substantially as shown and described.
